UNITED STATES PATENT OFFICE.

WILLIAM JOSEPH HOSCETT, OF CHICAGO, ILLINOIS.

LOCKING MECHANISM FOR DOORS.

1,311,562.

Specification of Letters Patent. Patented July 29, 1919.

Application filed October 25, 1917. Serial No. 198,442.

To all whom it may concern:

Be it known that I, WILLIAM JOSEPH HOSCETT, a citizen of the United States, and resident of Chicago, in the county of Cook and State of Illinois, have invented certain new and useful Improvements in Locking Mechanism for Doors, of which the following is a specification.

This invention relates to locking mechanism for railway car doors.

One of the objects of the invention is to make it necessary first to open a given door before it is possible to open a second given door.

Another object of the invention is to make it necessary first to close a given door before it is possible to close a second given door.

Another object is to provide an interlock between a plurality of doors whereby the same may be controlled in a manner to meet the various requirements for successful commercial use.

Generally speaking, these and other objects are accomplished by providing in a railway car, the combination of a plurality of movably mounted doors, a member operatively connected with one of said doors, and a latch, the movement of which is controlled by another of said doors for normally holding said member and its associated door in a given position.

The invention is illustrated on the accompanying sheets of drawings, in which—

Figure 1 is a fragmentary sectional view taken in the plane of line 1—1 of Fig. 2, showing the floor in plan and embodying my invention;

Fig. 2 is a fragmentary side elevation of a freight car embodying my invention;

Fig. 3 is a fragmentary transverse sectional view taken in the plane of line 3—3 of Fig. 2 and showing the drop doors locked in their raised or closed position;

Fig. 4 is a similar sectional view showing the drop doors in their lowered or opened position;

Fig. 5 is an enlarged detail plan view showing the latch for holding the drop doors closed, the movement of which latch is controlled by a side door; and,

Fig. 6 is a detail sectional view taken in the plane of line 6—6 of Fig. 5.

The various novel features of the invention will be apparent from the following de-

scription and drawings and will be particularly pointed out in the appended claims.

This invention is a modification of that disclosed and claimed in a copending application, Serial No. 198,441, filed October 25, 1917. The car 10 is provided with a center sill 11, intermediate sill 12 and side sill 13, which support various portions of the floor 14. In view of the fact that different sides of the car are symmetrical, only one side will be particularly shown and described. Drop doors 15 which form a portion of the floor of the car are preferably pivotally connected to the intermediate sills 12, and are arranged to swing downwardly and inwardly toward the center of the car. Each of the drop doors 15 includes an angle bar 16, the outer end of which tapers and is provided with serrations 17 which coöperate with serrated portions 18 of an operating shaft 19 which normally is located under the door for supporting the same in its raised or closed position, as particularly shown in Fig. 3. Wrapped around the operating shaft 19 at each end thereof is a chain 20, one end of which is secured to the shaft and the other end of which is secured to a bracket member 21 secured to and depending from the angle member 16 of the associated drop doors.

It is readily apparent that if the operating shaft in each case is actuated to move outwardly away from the center of the car, that it will pass from under the associated drop door, permitting the latter to swing downwardly into an open position in which it is supported by suitable means 22. The shaft 19 may be actuated in any suitable manner. In this particular case there are four of these shafts 19, one located in each one-quarter of the car, two being at each side and in alinement with each other longitudinally with respect to each other and to the car. It will be noted that each of the shafts 19 is supported at a plurality of points by supporting members 23 which are secured to the side sill 13 intermediate the floor 14 and transverse beams 24. Each of these supporting members 23 is provided with an elongated slot 25 in which the shaft 19 may move transversely, the outer end of each of the slots 25 having a depressed portion 26 in which the shaft 19 may rest when the shaft is moved to its extreme outward

position. Also connected to each of the shafts 19 at its inner end is a slidably mounted member 27. Preferably each of the slidably mounted members 27 has an opening in which the corresponding shaft is carried. Each of these members 27 is adapted to slide transversely with respect to the car and be guided in such movement by flange members 28. Normally, however, these slidably mounted members 27 are retained in their innermost position to positively hold the operating shaft 19 in a position to hold the doors 15 in their upper or closed position, said slidable members 27 normally being held in such position by a latch 29 which is pivotally mounted on a pin 30 connected to the side sill 13. It will be noted that this latch 29 is located substantially midway between the ends of the car and is arranged to retain the slidably mounted members 27 of the two adjacent operating shafts 19, so that when one of the shafts 19 is liberated the other shaft also is liberated.

From this arrangement it is apparent that if the latch 29 is rotated in a counterclockwise direction, as viewed in Figs. 2 and 5, through an angle of 90°, that said latch will have moved beyond the path of movement of the slidably mounted holding members 27 whereby the latter and also the shafts 19 are free to move outwardly, thereby permitting the drop doors 15 to fall into their lower or opened position. But in this connection it is to be observed that the latch 29 is not free to rotate from its normal horizontally arranged position unless the side door 34 of the car is moved to an open position beyond the latch 29, for the reason that the latch is located directly under the lower edge of the side door 34. It is seen, therefore, that it is necessary to open the side door first before the drop doors can be opened.

In connection with the complete operation of the door lock mechanism, let it be assumed that the seal of the side door has been broken and the door moved into an open position beyond the latch 29. The latch 29 is then swung 90° in a counterclockwise direction until its lower side passes into engagement with a stop member 31. The shaft 19, in each case, is then operated by any suitable mechanism to move the shaft 55 in an outward direction, whereupon it passes from under the drop doors 15, permitting the drop doors to swing downwardly into their open position, as shown in Fig. 4, the operating shaft 19 then resting in the depressed portions 26 of the slots 25 with the chains 20 completely unwound or sufficiently so to permit the drop doors 15 to rest upon the supports 22. During the outward movement of the shaft 19, the slidably mounted members 27 move outwardly beyond the ver-

tical plane of the latch 29. With the parts in this position, it is clearly apparent that it will be impossible to close the side door without first closing the drop doors 15, for the reason that the slidably mounted members 27 would not permit of the latch member 29 being swung back in a clockwise direction into its normal horizontal position. In other words, the locking mechanism forms a positive interlock between the side 75 door and the drop doors in the floor of the car. In order to close the doors, therefore, it is first necessary to actuate the shaft 19 in a manner to wind the chain 20 thereon, whereupon the drop doors 15 will swing upwardly into their closed position, the shaft 19 finally moving under the doors 15 and drawing the slidably mounted members 27 inwardly to a point where the latch 29 may be swung 90° in a clockwise direction to 85 positively lock the shafts 19 in their holding positions and permitting the side door to be moved into a closed position. By means of this arrangement it is apparent that a single seal secured to the side door is 90 sufficient for both the side and drop doors.

The latch member 29 has associated therewith at opposite ends bracket members 32 and 33 having inwardly extending lips behind which the outer portions of the latch 95 pass and preferably the lip on the bracket 32 or a portion of the latch 29 associated therewith, has a cam surface to make a relatively tight frictional holding connection between the latch 29 and one of its coöperating brackets to hold the latch in its normal locking position.

It is apparent that there may be various modifications of the invention herein particularly shown and described, and it is my 105 intention to cover all such modifications which do not depart from the spirit and scope of the invention as set forth in the following claims.

I claim:

1. In a railway car, the combination of a plurality of movably mounted doors, and locking means whereby it is necessary first to open a given door before it is possible to open a second given door, said locking means including shaft carrying members and a latch normally for holding said members in a given position.

2. In a railway car, the combination of a plurality of movably mounted doors, locking means whereby it is necessary first to open a given door before it is possible to open a second given door, said locking means including shaft carrying members and a latch normally for holding said members in a given position, and means normally for retaining said latch in its locking position.

3. In a railway car, the combination of a plurality of movably mounted doors, and

locking means whereby one must be closed before the other can be closed, said locking means including shaft carrying members and a latch normally for holding said members in a given position.

4. In a railway car, the combination of a plurality of movably mounted doors, and locking means whereby it is necessary first to actuate a given door before it is possible to actuate a second given door, said locking means including shaft carrying members and a latch normally for holding said members in a given position.

5. In a railway car, a plurality of movably mounted doors, locking means for said doors including a member for normally holding one of said doors in a closed position, a slidably mounted member connected to said first mentioned member, and a pivotally mounted latch for normally directly holding said slidably mounted member in a locking position.

6. In a railway car, a plurality of movably mounted doors, locking means for said doors including a member for normally holding one of said doors in a closed position, a slidably mounted member connected to said first mentioned member, and a latch for normally engaging and holding said slidably mounted member in a locking position, said latch normally being held in its locking position by another one of said doors.

7. In a railway car, the combination of a door movably mounted in the floor of the car, a shaft normally located under said door for holding the latter in its closed position, a supporting member for said shaft permitting lateral movement of the shaft whereupon the door may be opened, a shaft carrying member and a latch normally engaging said shaft carrying member and causing said shaft to remain in a position for holding said door.

45 8. In a railway car, the combination of a door movably mounted in the floor of the car, a shaft normally located under said door for holding the latter in its closed po-

sition, a supporting member for said shaft permitting lateral movement of the shaft 50 whereupon the door may be opened, a shaft carrying member, a latch normally engaging said shaft carrying member and causing said shaft to remain in a position for holding said door in closed position, and a 55 side door for holding said latch in a locking position.

9. In a railway car, the combination of a side door, a door movably mounted in the floor of the car, a shaft normally located 60 under the door for holding the latter in a closed position, a support for said shaft having an elongated opening to permit movement of said shaft to permit opening of said door, a movably mounted member in which 65 said shaft is mounted, and a latch associated with said side door for coöperating with said movably mounted member normally to retain said shaft in its holding position.

10. In a railway car, the combination of 70 a plurality of movably mounted doors normally sustained by shafts, and locking mechanism between said doors including a pivotally mounted latch directly controlling releasing movement of said shafts, the releasing movement of the latch being controlled by one of said doors.

11. In a railway car, the combination of a plurality of movably mounted doors normally sustained by shafts, locking mechanism between said doors including a pivotally mounted latch directly controlling releasing movement of said shafts, the releasing movement of said latch being controlled by one of said doors, and means for 85 limiting movement of said latch.

12. In a railway car, a plurality of door retaining shafts, and a single latch the ends of which are operatively associated with said shafts for locking all of said shafts in 90 a given position.

Signed at city of Chicago, State of Illinois, this 25th day of September, A. D. 1917.
